STORAGE BOX

Robert F. Davis, West Palm Beach, Fla.

Application June 4, 1946, Serial No. 674,220

3 Claims. (Cl. 312—112)

I

This invention relates to retractable storage boxes and more particularly to an improved type of retractable storage box especially designed to utilize space that is otherwise wasted.

The problem of providing a sufficient amount of readily available storage space is a problem in every household. Regardless of the number of clothes closets, drawers, and even storage places under beds, under window seats and in kitchen cupboards, there is always a demand for still more storage space so arranged that the contents are readily accessible. One particular problem has been the storage of shoes and it has been mainly for the purpose of providing a better storage arrangement for shoes that the present invention has been made.

Shoe racks have been built into closets, under beds and in dresser drawers. Shoe boxes have been placed in closets and shoe racks fastened to closet doors. None of these arrangements has been entirely satisfactory. In many of them the shoes become dusty or rub against other garments and in others the shoe boxes or shoe racks clutter up the closet floor or provide an undesired obstacle on the door of the closet. The present invention avoids the difficulties, keeps the shoes easily accessible, substantially dust-free, off of the floor and out of the way.

Briefly, the present invention comprises a box adapted to contain shoes or any other object or objects which are to be stored and which box is particularly adapted to be mounted just above and just inside of the door of a clothes closet. The box is so mounted that it normally occupies the space just above and just inside of a closet door, which space is otherwise unoccupied and unused. The box is also mounted so that it can be pulled downward to a position below the upper sill of the closet door and one face of the box is open to permit easy access to the contents, when the box is in its lowered position. Thus, when the box is properly installed, it remains out of sight and out of the way just inside of and above the closet door. When it is desired to reach the contents, the box is pulled to a lower position by means of a handle affixed to it, and while in this position, the contents may be inserted or removed. By providing a spring or counter-weighted suspension, the box may be caused to remain in either its uppermost or its lowermost position once it has been placed there and regardless of whether or not it contains an object or objects to be stored. Thus, once the user pulls the box down, it can be arranged to stay down until the user takes from or places in the

2

box an object or objects, and then, after the user has pushed the box into the uppermost position, the box will stay in that position until the user again pulls it down.

Further details and advantages of this invention will be apparent from the appended drawings and the following detailed description of the embodiments illustrated therein.

In the drawings:

10 Figure 1 is a rear elevational view of a device embodying the principles of this invention mounted in an ordinary clothes closet.

Figure 2 is a side sectional view of the same device taken on lines 2—2 of Figure 1.

15 The ordinary clothes closet door comprises a door frame 10 mounted in an opening in a wall 11. The preferred form of the device of this invention comprises a U-shaped frame 12 mounted on the upper end of the door frame 10 by a series of screws 13. The U-shaped frame 12 is preferably of such a shape that it will fit over the upper end of the door frame 10 and extend a distance of some twelve or fourteen inches above it. On this frame is mounted a box 14, by means of a pair of metal bales 15 and 16. Each of the bales is of U-shape with out-turned ends. The ends of the U-portion extend into openings 17 cut in the frame 12 and the out-turned ends are received in holes drilled laterally through the frame 12 into the openings 17. The bales 15 and 16 are thus mounted in the frame 12 at each end and in such a manner that they are free to rotate through an arc of 90° or more.

20 30 The box 14 is connected to the center section of each of the U-shaped members by means of hangers 18 mounted on the bottom and top thereof. By this arrangement the box is positioned laterally in the closet and prevented from tilting, but at the same time is permitted to move up and down from a position just above the top of the closet door to a position somewhat below the top of the closet door and back again.

25 35 When the box is in its uppermost position as shown in full lines in Figure 2, the space nearest the closet door is closed by the upper part of the frame 12. When it is in its downwardmost position, the same side of the box is left open and hence the box is readily accessible to a person standing just outside of the closet doorway. A spring 19 fastened to the upper end of the frame 12 and to the middle of the upper bale 15 serves to hold the box in its upward position. If the spring is of the proper strength, it will hold the box in its upper position but will not move from its downward position, once it has

been lowered, because of the decreased leverage which it has when the box is in the lowered position.

A handle 20 or a pull cord, may be placed on the lower face of the box to assist the user in lowering or raising the box. The box itself, and the other parts of the device, may be made either of metal, plywood, plastic, or any other desired material. The box may contain partitions 21 and 22 dividing it into a series of compartments for shoes or the like. If desired, these partitions can be made to be removable so that they can be used, or not, at will.

In some instances, it will be found desirable to slope the rear wall of the box making the box somewhat narrower at its lower end so that it will miss the shelves in a very shallow closet, or will afford more room for access to the shelves when it is in its upper position. In such a case, for example, the box might be deep enough for women's shoes in its lower shelf and deep enough for men's shoes in the upper shelf and still be shallow enough in depth to be satisfactory in a quite shallow closet.

Although the box illustrated has been shown as mounted upon a pair of U-shaped bales 15 and 16, it can be mounted upon slides, or some mechanical arrangement different from either of these may be used to move the box from its upper position to its lower position. Furthermore, by properly shaping the bales or slides, or properly arranging the other lowering mechanism, the box can be caused to move downward until it clears the upper edge of the door and then moved both downward and outward so that its final position is somewhat below the top of the door and somewhat ahead of the rear face of the door jamb.

The preferred application of the principles of this invention is to the use of otherwise waste space just above and just inside of a clothes closet door. It is contemplated, however, that such boxes may be used over other doors or even in places where there are not doors but where it is desired to store something in an otherwise wasted overhead space. The principal object of the invention, however, is the utilization of the waste space just inside and just over the door of a clothes closet or the like and it is here that the invention finds its most useful application.

What is claimed is:

1. In a construction of the type described, a room of the nature of a clothes closet, a doorway for access to said room, the top of said doorway being positioned a substantial distance below the ceiling of the room, thus leaving a normally unused space just above and just inside of the doorway, a box of a size and shape to be received in said space, means adapted to be attached to the wall above the doorway and to support said box in said space, and to permit said box to be lowered for a limited distance to a position below the top of the doorway, said means being arranged to at all times maintain said box against rotation, said box having an opening in one face thereof which is closed by the wall of the closet when the box is in its upper position and through which the contents of the box are accessible from the doorway when the box is in its lower position.
2. A retractable storage box for use at a doorway that comprises a supporting frame adapted to be attached to the wall above the doorway, a box normally adapted to be positioned horizontally adjacent said frame and having the side adjacent said frame open, a reciprocating connection between said frame and said box for maintaining said box against rotation but permitting said box to move downwardly to a position below the frame and upwardly to a position in horizontal alignment with said frame, and counterbalancing means connected between said frame and said box for counterbalancing the weight of said box.
3. A retractable storage box as defined in claim 2 further characterized in that partitions are provided in the said box for dividing it into a plurality of compartments each adapted to receive a pair of shoes.
